Primary Examiner — T. Chase Nelson*Assistant Examiner* — Jonathan J Han(74) *Attorney, Agent, or Firm* — Schwabe Williamson & Wyatt(57) **CLAIM**

The ornamental design for a firearm barrel nut, as shown and described.

DESCRIPTION

FIG. 1 is an isometric view of an embodiment of my firearm barrel nut illustrating an ornamental hole pattern; and, FIG. 2 is a side view of the firearm barrel nut and the ornamental hole pattern shown in FIG. 1.

The broken lines are included for the purpose of illustrating the environment and form no part of the claimed design.
